MELANCHTHON O. FELKER, OF CHICORA, PENNSYLVANIA.

WHIP.

No. 842,089.

Specification of Letters Patent.

Patented Jan. 22, 1907.

Application filed October 19, 1905. Serial No. 283,369.

To all whom it may concern:

Be it known that I, MELANCHTHON O. FELKER, a citizen of the United States, residing at Chicora, in the county of Butler and

5 State of Pennsylvania, have invented certain new and useful Improvements in Whips, of which the following is a specification, reference being had therein to the accompanying drawings.

10 This invention relates to improvements in horse-whips, particularly of the kind known as "carriage" and "buggy" whips.

The invention consists, essentially, in a means of building up the load-rod cheaply 15 and quickly to a proper diameter and proper conformation or taper to fill the interior of an expensive and finished handle—say a celluloid handle—made with a thin wall, so that while having the required diameter or size it 20 will still also be very light and thin for purposes of economy in the cost of such expensive type of handle. In the manufacture of fine whips with celluloid, ivory, or other highly expensive coverings or handles proper 25 much expense is entailed in the production and use of this one feature.

It is to preserve the body and finish so obtained and yet eliminate by far the larger part of the cost of such a handle that my invention is designed. This I accomplish, as 30 attested in actual manufacture, by the means hereinafter more fully described, and particularly pointed out in the claim. I may add, however, that I also utilize this invention for 35 the purpose of building up a load-rod even in cases where some other character of finish to the handle is employed.

In the accompanying drawings, Figure 1 is a side elevation of a buggy or carriage whip. 40 Fig. 2 is an enlarged longitudinal sectional view of the handle and a small portion of the body of such whip, showing my improvements; Fig. 3, an enlarged view showing a rod wrapped or built up according to my invention and of length sufficient to constitute two load-rods, and Fig. 4 a detail enlarged view of a building-up sheet.

The letter A designates a carriage or buggy whip preferably having an expensive and ornamental handle proper composed of a celluloid or ivory tapering tube B. The body of the whip carries a screw-threaded band C, on which is screwed one end of a coupling D, the other end of the coupling being fitted over 45 the part B and secured upon it and the building-up filling by being swaged or otherwise

forcibly indented into the same, as shown at E; but in respect to these matters other forms of construction may be employed to unite the whip-body with the handle portion. 60

The letter F designates the load-rod, composed, preferably, of a section of steel or other heavy material possessing strength also. In practice it is more economical to construct the load of a solid bar or rod rather 65 than in tubular form—as, for instance, of sheet-steel bent into such form. I therefore prefer a solid-steel load-rod; but the required size of this load-rod is so much smaller than the required size of the expensive and ornamental covering or handle proper, B, when the same is made with its wall thin enough to be economical that resort must be had to means for building up the load-rod of the required size, as well as the required shape, to readily 70 enter and fill up such covering. This I accomplish by means of one or more layers or sheets of material, preferably paper, cut in the form shown at G in Fig. 4. This building-up sheet has its opposite sides H parallel, 75 or substantially so, for a portion of its length—say about one-third. This much of the sheet is of a width slightly in excess of the length of the load-rod, the excess allowing for trimming off. The load-rod is then wrapped 80 with the building-up sheets, with the rod in the position shown in dotted lines in Fig. 4. In this way the whole length of the rod is built up while a part of the sheet is being wound on it. Then from the point I on the 85 sheet to its end J the rod is built up less and less from one end toward the other until finally when the whole sheet is wrapped on the rod it has the tapering form indicated in Figs. 2 and 3 and is not only of the shape, but 90 also of the size required to enter and fill completely, solidly, and firmly the thin tubular covering or handle proper, B, being inserted into its larger end. Glue or some other adhesive is used on the building-up sheet to 95 make the coils adhere together. For convenience in manufacture two or more load-rods are so built up at once and then the rod severed to make separate loads. Usually 100 two or three sheets are stuck together and wound on the rod at the same time, so as to more rapidly build it up.

Referring to Fig. 2, it will be seen that the larger end of the covering B is provided with a finishing-cap K, which is compressed down 110 on the covering and built-up portion, as seen at L, to secure the cap. A rubber tip M may

be inserted between the end of the cap and the end of the load to close the cap and to form a cushion against marring the cap when the whip is inserted into the socket or is allowed to strike the floor or ground.

Thus it will be seen that by my improved means of building up a whip load-rod I effect great economy and at the same time make a firm and exactly-suitable structure for the purpose intended. It will be understood that I may utilize this built-up load-rod in connection with other kinds of final handle-coverings than that above set forth.

Having thus fully described my invention, what I claim as new, and desire to secure by Letters Patent, is—

In a whip, the following devices: a load-rod; a strip of material for building up a filling on said load-rod composed of a sheet having one edge substantially straight through-

out its length, and the other edge substantially parallel thereto for a part of its length and thence running obliquely toward the first-named edge, whereby when said strip is wound on said rod the filling to the extent of 25 a portion of its thickness will be equally built up over the whole length of the rod, and thence will be built up and finished in a tapering form, a rigid thin-walled tubular covering fitted over said built-up filling, and a 30 coupling having one end secured upon said covering and the other end extending beyond the same for attachment to a whip-body.

In testimony whereof I affix my signature in presence of two witnesses.

MELANCHTHON O. FELKER.
